LIGHT SWITCH CONTROL

John Fanzoi, Chicago, Ill.

Application November 15, 1946, Serial No. 709,893

5 Claims. (Cl. 200—54)

1

This invention relates to a light switch control and particularly to a means for controlling an electric light in a closet, room or the like by means of a door or the like. The invention is particularly adapted to provide a simple device for use with a conventional pull-chain light switch to be controlled by a door. A structure embodying the present invention is simple, cheap to manufacture and may be installed quickly and easily.

In order that the invention may be disclosed, reference will now be made to the drawings. Figure 1 shows a top view partly in section of a device embodying the present invention secured in position in a door. Figure 2 is a side elevation partly in section of the structure shown in Figure 1. Figure 3 is a section on line 3—3 of Figure 2. Figure 4 is an end elevation of the base plate showing the up-turned eyeleted portions. Figure 5 is a perspective view of an angle iron which may be used.

The device comprises base plate 10 of sheet metal or other rigid material having up-turned corners 11 and 12. Corners 11 and 12 are turned up to extend from the same face of the plate and are apertured as shown. Eyelets 13 and 14 are preferably provided at the corner apertures to provide smooth-bearing surfaces. Plate 10 carries pivot pin 16 extending upwardly therefrom on the same side of the plate as corners 11 and 12. Pivot pin 16 is located substantially equidistant from eyelets 13 and 14, the exact distance being unimportant.

Pivotedly mounted on pin 16 is rocker plate 17, this plate being generally flat and having four outwardly extending fingers 18 to 21 inclusive. Fingers 18 and 19 have a substantial angle formed thereby, while fingers 20 and 21 in general will have a smaller angle between them. Preferably, though not necessarily, the four fingers are symmetrically arranged. Fingers 18 and 19 have attached thereto ends 23 and 24 of rope 25 having substantial stiffness. Rope 25 may consist of stranded steel or iron wire forming wire cable. The cable ends may be soldered or spot welded to fingers 18 and 19 or the fingers may be crimped to bind the cable ends. Cable 25 has collar 26 binding the cable to form small loop 27 at the mid-portion of the cable.

Collar 26 and loop 27 are small enough to pass through the eyelets so that the cable may be threaded through an eyelet as shown. It will be noted that cable ends 23 and 24 extend from fingers 18 and 19 symmetrically. When the cable is threaded through an eyelet, rocker plate 17

2

will normally assume a position like that in Figure 1 where fingers 18 and 19 are symmetrical with respect to the eyelet through which the cable passes.

5 Base plate 10 has apertures 33 and 34 at suitable places for mounting purposes. Thus, referring to Figures 1 and 2, top member 33 of a door frame may have base plate 10 attached thereto by suitable screws 34. The base plate is attached in such a manner that pivot pin 16 and corners 11 and 12 extend downwardly toward the floor with corners 11 and 12 being disposed within closet space 35. Cooperating with part 33 of the door frame is door 36 mounted on suitable hinges 37.

10 For actuating rocker plate 17, any suitable means such as angle iron 38 may be provided. Angle iron 38 has arms 39 and 40, one or both of the arms usually being apertured for mounting purposes. Thus, as shown here, arm 39 has mounting apertures 41. Angle iron 38 is carried on door 36 by wood screws 42 passing through apertures 41. The angle iron may be mounted on the door in any suitable fashion so that arm 25 40 will extend toward rocker plate 17 and be in a position to cooperate therewith. Pull cord 44 going to lighting fixture 45 is tied to loop 27 of the wire cable. Cord 44 is pulled tightly enough so that rocking of plate 17 will be sufficient to 15 operate the pull switch.

20 Normally, the rocker plate is in the position shown in Figure 1 when door 36 is closed. Upon opening of the door, arm 40 of the angle iron is turned and engages finger 20. When the door has been opened sufficiently, arm 40 of the angle iron will trip the rocker plate enough to operate the light switch and pass beyond finger 20. The normal stiffness of wire cable 25 will cause the rocker plate to return to the position shown 25 in Figure 1, even though the door is now open. Upon closure of the door, arm 40 will engage finger 21 and turn the rocker plate clockwise, as seen in Figure 1, to actuate the light switch again. With the door fully closed, arm 40 will sweep past finger 21, and the rocker plate will again 30 return to its normal position.

35 For a door with the hinges on the left side, as seen in Figure 1, the arrangement of cable and eyelet, as shown in this figure, is satisfactory. If a door has hinges on the opposite side, then wire cable 25 may be threaded through the other eyelet, as seen in Figure 3 for example. It is understood that the wire cable must be threaded through the correct eyelet prior to tying the light cord thereto.

It is evident that the invention provides a structure which is easy to install and effective in operation.

What is claimed is:

1. In a device of the character described, a base plate, a flat member having at least two spaced fingers, means for pivotally mounting said member on said base plate, means on said base plate providing a smooth aperture, a length of stiff cable looped through said aperture with the two ends extending toward said member and attached thereto at spaced points, said member having the two points of attachment of said cable ends oppositely disposed to the fingers of said member, said base plate being adapted to be mounted in a door frame adjacent a door, an actuating member adapted to be attached to said door and to engage said fingers of said member to move the same through suitable angles, said looped cable being adapted to be secured to a pull-chain switch whereby movement of the door will control the condition of said switch.

2. The structure of claim 1 wherein said plate has two spaced points provided with apertures through one of which the cable may be threaded for use with right or left-hand doors.

3. In a device of the character described, a base plate, a flat rotatable member having four fingers, means for pivotally securing said member to said base plate, an apertured portion carried by said base plate adjacent said member, a short length of wire cable doubled on itself having the ends threaded through said aperture toward said member, means for securing said cable ends to two of said fingers, said cable ends being separated from each other and at a sufficient distance from the aperture so that two resilient portions of the cable are provided, the free cable loop being adapted to be secured to the cord of a pull-chain electric switch, and an elongated rigid member, said base plate being adapted to be attached to a door frame adjacent a door and said elongated member being adapted to be attached to a door, said elongated member cooperating with two remaining fingers whereby, upon opening of a door from a closed position, said member is moved in one direction and, upon closing of the door, said member is moved in another direction, the movement of said member in each case being sufficient to actuate said pull-chain switch, said wire cable returning said member to

a normal rest position after each movement thereof.

4. The structure of claim 3 wherein said base member has two apertured portions symmetrically disposed with respect to the axis of said member whereby said cable may be threaded through either of said apertured portions for use with right or left-hand doors.

5. In a device of the character described, a metal base plate having a generally rectangular shape, said base plate having two adjacent corners turned up, said corners being apertured at the upturned portions, a flat member having four fingers, means for pivotally mounting said member on said base plate with the pivot axis being equi-distant from said two turned-up corners, a short length of wire cable doubled on itself, means for attaching each end of said cable to two adjacent fingers, the doubled portion of the cable being adapted to be threaded through one of said two apertured corners, said fingers retaining the cable ends being spaced sufficiently so that movement of said member on its pivot from either side of a normal position is resisted by the wire cable, said base plate being adapted to be attached to a door frame adjacent the hinged side of a door and an actuating finger adapted to be carried by said door, said actuating finger cooperating alternately with one of the two remaining fingers to move said member from a normal position alternately in opposite directions, said looped end of the cable being adapted to be secured to a pull-chain electric switch whereby the switch may be actuated by opening and closing door movements, said cable being adapted to be threaded through the proper upturned corner depending upon whether the door is right-hand or left-hand.
